United States Patent Office

Des. 173,708
Patented Dec. 21, 1954

173,708

WATER AND SOAP MIXING UNIT

Paul F. Otto, Detroit, Mich.

Application October 27, 1953, Serial No. 27,354

Term of patent 14 years

(Cl. D91—3)

Fig. 1.

Fig. 2.

Fig. 3.

To all whom it may concern:

Be it known that I, Paul F. Otto, a citizen of the United States, residing at Detroit, county of Wayne, State of Michigan, have invented a new, original, and ornamental Design for a Water and Soap Mixing Unit, of which the following is a specification, reference being had to the drawing, forming a part thereof.

Fig. 1 is a top plan view of a water and soap mixing unit embodying my new design.

Fig. 2 is a front elevation.

Fig. 3 is a side elevation, the opposite side being similar in appearance thereof.

I claim:

The ornamental design for a water and soap mixing unit, as shown and described.
